(57) **CLAIM**

I claim the ornamental design for a remote control car, as shown and described.

DESCRIPTION

FIG. 1 is a front perspective view of a remote control car.
FIG. 2 is a rear perspective view of the remote control car of FIG. 1.

FIG. 3 is a front view of the remote control car of FIG. 1.

FIG. 4 is a back of the remote control car of FIG. 1.

FIG. 5 is a side view of the right side of the remote control car of FIG. 1.

FIG. 6 is a side view of the left side of the remote control car of FIG. 1.

FIG. 7 is a top view of the remote control car of FIG. 1.

FIG. 8 is a bottom view of the remote control car of FIG. 1. The broken lines shown are included for the purpose of illustrating portions of the article which form no part of the claimed design.

1 Claim, 7 Drawing Sheets
